UNITED STATES PATENT OFFICE.

HARRY E. MUCHNIC, OF ATCHISON, KANSAS.

RAILROAD GRADE-CROSSING.

1,154,584.

Specification of Letters Patent. Patented Sept. 21, 1915.

Application filed July 14, 1915. Serial No. 36,876.

To all whom it may concern:

Be it known that I, HARRY E. MUCHNIC, a citizen of the United States, residing at Atchison, in the county of Atchison and State of Kansas, have invented new and useful Improvements in Railroad Grade-Crossings, of which the following is a specification.

This invention relates to a railroad crossing for use where a street, road, or public highway intersects a railroad track at grade; and is intended to provide a strong and simple iron grade crossing of few parts capable of being easily installed and as readily removed for purposes of repair of the track.

Another object in view is to form a crossing of a limited number of metal plates placed between the rails and extending across the track from rail to rail, and of other metal plates arranged on the outside of said rails, all of which plates shall be secured in position solely by screws, bolts, or equivalent means passing through the plates into the cross ties. The plates rest at their ends upon the base flanges of the rails, and are thereby given a rigid support for the loads; and, by means of the fastening bolts, lateral movement of the plates is prevented. No connection between the plates and rails being needed, no special parts are used for the attachment, nor are additional bolt holes necessary in certain of the rails, thus enabling the crossing to be placed wherever required.

In the accompanying drawings, illustrating the preferred form of the invention, Figure 1 is a plan view of a crossing over a single track railroad. Fig. 2 is a cross sectional view on the line 2—2 of Fig. 1. Fig. 3 is a perspective view of one of the crossing plates, in inverted position, as used between the rails. Fig. 4 is a similar view of one of the plates designed to be placed against the outside of the rails to form the approach to the track. Fig. 5 is an enlarged sectional view of one track rail and elevations of parts of two plates supported on the rail flanges.

The track rails are indicated by A and the cross ties by B, and do not differ from such as are in common use. Between the rails A and extending transversely of the track are placed a plurality of rectangular plates 10 which may be made of cast iron or steel, pressed steel or other suitable metal. Each of these plates is sufficiently long to extend

from rail to rail and has a width of about one half its length. The plates have a slight regular convex curvature in a longitudinal direction for the greater part of their length, 60 but a quick downward and outward bend 11 at their ends serving to lower these ends so that they shall pass under the heads of the rails. A channel 12 is thus formed at the inner or gage edges of the rails A to provide clearance for the wheel flanges of passing trains. A depending flange 13 is formed on each end of each plate 10, and a like flange 14 on each side thereof; and if found desirable or necessary a longitudinal rib 15 70 may be formed between the side flanges 14. When in position the end flanges 13 of the plates 10 rest upon the inner base flanges 16 of the rails A and hold the plates out of contact with the ties B. A rigid support is 75 thus given to the plates which, being free from the cross ties, cannot cut into them under traffic and be loosened. Lag screws 17, spikes, or other suitable fastenings pass through holes 18 in the corners of the plates, 80 and are driven into the ties. The holes 18 are countersunk to bring the heads of the fastening means below the surfaces of the plates. The plates may be smooth on their wearing surfaces or roughened. They may 85 also be provided with holes through which dirt may work.

The approaches to the track on each side are made of several rectangular metal plates 19, preferably of a length equal to the width 90 of two plates 10. The plates 19 are placed end to end parallel with the rails A with one side in contact with the outer edge of the rail. The width of these plates may vary, but by preference is less than their 95 length. The inner edge of each plate 19 has an under flange 20 which rests on the outer edge 21 of the adjacent rail A; and also two longitudinal ribs 22 reaching downward to the cross ties, and which resting thereon assist the flange 20 in supporting the plate 19. The sides of the plates 19 extend beyond the outer ribs 22 and bear upon the material forming the street or highway, 100 their upper surfaces being continuous with the ground surface. These approach plates 19 may, as shown, be given a slight downward inclination away from the rails if the grade of the highway demands it. Lag screws 23, or other fastening means passing through holes 24 at the inner corners of the 105 approach plates, secure said plates to the 110

ties as in the case of the plates 10. The plates 19, if desired, may be roughened and perforated.

When the crossing intersects a double track road, or where several tracks lie parallel to each other, the space between the tracks may be filled with plates similar to the described plates 10.

The width of the crossing and the number 10 of plates used will depend upon the amount of traffic passing over the road. No fitting of parts being necessary to install these plates, crossings may with speed and economy be laid, or increased or decreased in 15 width.

Constructive features entering into this device may, without the exercise of invention, be variously modified in accordance with the wishes of the skilled mechanic, and 20 such changes as do not involve invention I consider as within the scope of my claims.

Having thus described my invention, I claim:—

1. A railroad crossing comprising a plurality of metal plates extending transversely 25 between the rails of the track and supported at their ends on the rail flanges, a plurality of plates adjacent to the outer sides of the rails and supported at one side by the outer 30 flanges of the rails, and means for securing the plates to the cross ties.

2. A railroad crossing comprising a plurality of metal plates extending transversely 35 between the rails of the track and supported at their ends above the cross ties and out of contact therewith by the rail flanges, a plurality of longitudinally extending plates adjacent to the outer sides of the rails and supported at one side by the outer flanges 40 of said rails, and means for securing each plate solely to the cross ties.

3. A railroad crossing comprising a plurality of metal plates extending transversely 45 between the rails of the track and supported by depending flanges on the ends of said plates bearing on the rail flanges, a plurality of plates adjacent to the outer sides of said rails and supported on the outer rail flanges by a depending flange, and means for 50 securing the plates to the cross ties of the track independently of the rails.

4. A railroad crossing comprising a plurality of metal plates extending transversely 55 between the rails of a track and supported only at their ends on the rail flanges, and means for securing said plates to the cross ties.

5. A railroad crossing comprising a plu-

rality of metal plates extending transversely between the rails of the track and supported 60 at their ends on the rail flanges, the ends of said plates being depressed to provide clearance for the wheel flanges of passing trains, a plurality of plates adjacent to the outer sides of the rails and supported at one side 65 by the outer flanges of the rails, and means for securing the plates to the cross ties.

6. A railroad crossing comprising a plurality of metal plates extending transversely 70 between the rails of the track and supported solely on the rail flanges by depending flanges on the ends of said plates, said ends being so depressed as to pass beneath the heads of the rails and provide clearance for the wheel flanges of moving trains, a plurality of approach plates adjacent to the outer sides of the rails and supported at one side by the rail flanges, and means for securing the plates to the cross ties. 75

7. A crossing plate for railroad crossings 80 comprising an integral rectangular metal structure having a depending flange at each end and a like flange at each side, the ends of said plate being depressed, said plate being perforated at each corner for the passage of 85 a securing device.

8. An approach plate for rail crossings comprising a rectangular metal plate having a depending flange on one side and depending ribs parallel with said side, said plate 90 having perforations in the corners adjacent to the flange for the passage of securing means.

9. A railroad crossing comprising a plurality of curved metal plates extending 95 transversely between the rails of the track and having depending flanges on their ends adapted to bear on the rail flanges and support the plates above the cross ties, a plurality of plates adjacent to the outer sides 100 of the rails, each plate having a depending flange along one side edge that bears upon the outer rail flange and supports the plate at said side, all of said plates having perforations through the corners near the rails, 105 and bolts or screws passing through said perforations into the cross ties and forming the sole means for fastening the plates in position.

In testimony whereof I affix my signature 110 in presence of two witnesses.

HARRY E. MUCHNIC.
